UNITED STATES PATENT OFFICE.

ANGUS R. GROSS, OF BALTIMORE, MARYLAND.

DESIGN FOR A PARKING LIGHT.

Application filed May 13, 1921. Serial No. 469,388. Term of patent 7 years.

To all whom it may concern:

Be it known that I, ANGUS R. GROSS, a citizen of the United States, residing at Baltimore, State of Maryland, have invented a new, original, and ornamental Design for a Parking Light, as shown in the accompanying drawing, forming part of this specification.

In said drawings:—Fig. 1 is an end view of the lamp casing, and Fig. 2 is a side view thereof; and Fig. 3 is a top view.

Claim.

I claim the ornamental design for a parking light substantially as shown.
